UNITED STATES PATENT OFFICE.

ORIN WEEMAN, OF LYNN, MASSACHUSETTS.

IMPROVEMENT IN CHANNEL-OPENER FOR BOOT AND SHOE SEWING MACHINES.

Specification forming part of Letters Patent No. 97,330, dated November 30, 1869.

To all whom it may concern:

Be it known that I, ORIN WEEMAN, of Lynn, county of Essex, and State of Massachusetts, have invented an Improved Channel-Opener for use on Boot and Shoe Sewing Machines; and do hereby declare the following to be a full, clear, and exact description thereof, reference being had to the accompanying drawings, in which—

Figure 1 shows my channel-opener turning the lip of a channel previous to sewing. Figs. 2 and 3 are detailed views, showing more plainly the peculiar construction of the foot-share and mold-piece of the opener.

The object of my invention is to produce a channel-opener to be attached to sewing-machines for work on boots and shoes in front of the needle, so that it will turn back the lip of the channel as fast as the sewing requires, the lip to be turned in such a manner that the grain of the leather will not be broken, and that will allow the lip to fall back to its place, where it can be easily stuck down.

The nature of my invention consists in a point or shoulder, which runs in the channel, above which point is a mold-piece, like a plow, made in such form as to raise and turn the lip of the channel like a furrow, leaving the work free for the needle. The presser-foot is above the opener, in such relation to it that it steadies the opener, the opener being attached to the upper part of the presser-foot by a spring. This spring allows the easy passage of the opener over uneven places in the leather, while the opener cannot be raised higher than the presser-foot will allow, it being fixed in its position.

At present channels are cut in the soles by channel-machines; but they are opened by hand, and the lip turned back before the sole is ready for the sewing-machine. It is often necessary to hammer the lip back to keep the channel open. This breaks the grain of the lip, and is a damage to the sole. It often occurs that the thread, in the process of sewing, will catch the edge of the lip of the channel and sew it down, making a bad place in the edge of the sole, or obliging the operator to stop to free the lip from the thread.

My improved channel-opener overcomes these objections, saving the work of the hand-opening of the channel, while, by its employ-

ment, the channel is opened as fast as required, and in such a manner that there is no danger of thread catching the lip of the channel, nor of breaking the grain of the leather, while the work is done with more satisfaction to the operator, and the result is a neater and more serviceable shoe or boot.

Practical experience has taught me the advantages of using a channel-opener upon the sewing-machine.

In the drawings, A is the presser-foot of a sewing-machine, the toe a being adapted to use with my improved channel-opener, instead of being formed as usual. B is a spring-arm, attached at F to presser-foot A, and extending from F along the foot A a little beyond the toe a. At the lower part of this arm B is a shoulder or projection, c, which, when the machine is in operation, runs in the channel E of the sole S. This keeps the opener in place, and preserves a steadiness of the whole. Back of and above the shoulder c is the share or opener H d, which runs under the lip of the channel, and as it extends upward forms the mold-piece d, which turns the lip up and over sufficiently to clear it from the needle of the machine.

The shoulder c, which has corrugations on its face to prevent its slipping, may be longer—that is, it may extend from c to H, Fig. 2, or part of the way—but the form shown is convenient in use. The form of the mold-piece may be varied, but it will be found that the shape shown will accomplish the purpose sought.

The spring-arm keeps the shoulder c in the channel at all times, whereas, if the opener was formed on the foot A, it would be lifted out of the channel by the motion of the machine. This spring-motion may be introduced in different ways—for instance, by joint in the presser-foot, and spring attached, or by spring in the rod above the presser-foot; but the movement would be the same as produced by the devices shown—that is, the dragging motion of the opener under the foot A.

The operation of my invention is simple, and is easily understood from the drawings and description. Its advantages have been set forth above.

What I claim as my invention, and desire to secure by Letters Patent, is—

1. The spring-arm B, attached to the presser-foot of a sewing-machine, as shown, and having shoulder or point *c* and share or mold-piece *d* *H*, substantially as herein set forth.

2. A channel-opener formed by the combination of spring-arm B, shoulder or point *c*, and share or mold-piece *d* *H*, substantially as set forth.

3. The combination of the above-described

channel-opener and the presser-foot A, substantially as set forth.

In testimony whereof I have signed my name to this specification in the presence of two subscribing witnesses.

ORIN WEEMAN.
